UNITED STATES PATENT OFFICE.

ARTHUR L. STANFORD, OF LIBERTYVILLE, ILLINOIS.

RAIL ANCHOR.

Application filed November 17, 1926. Serial No. 148,821.

I am the Arthur L. Stanford to whom Letters Patent of the United States were issued as follows: viz: No. 1,196,488, dated August 29, 1916; No. 1,257,602, dated May 28, 1918; No. 1,347,301, dated July 20, 1920, and No. 1,406,295, dated February 14, 1922. In the rail anchor of each of the above patents the body portion is substantially identical with the body portion of the rail anchor of my present application. All of said cited patents comprise a holding jaw which fits snugly upon and frictionally engages the rail flange, with a depending foot which is driven against the tie by rail creeping and gives to the anchor a tendency to tilt or cant longitudinally of the rail. Also, all of the patents above cited are provided with a rigid, integral, relatively heavy cross bar provided with means for attaching to the far edge of a rail, whereby the body of anchor is retained in service position upon the rail when the foot of the anchor is not pressing against the tie. The anchor of my present application omits the integral cross bar above mentioned.

I have now discovered that a separately formed, relatively light, and, therefore, inexpensive wire spring meets the requirement of holding the anchor against transverse displacement.

My objects are to reduce the weight and manufacturing cost of the anchor; to simplify the same; to make possible quick application to the rail; to produce an anchor which can be readily removed and reapplied; also to produce an anchor the body of which is particularly adapted to be made a malleable iron casting, which is known to be more resistant to oxidation than spring steel, and otherwise better adapted for use as a rail anchor.

Further objects will appear from a detailed description of the invention in conjunction with the accompanying drawings wherein—

Figure 1 is a front elevation of the anchor, partly in section showing it in gripping relation with the rail;

Fig. 2 is a similar view showing the anchor slightly canted and in position to be driven in place upon the rail;

Fig. 3 is an inside elevation of the anchor looking inwardly toward the opening between the jaws; and

Fig. 4 is a perspective view of a modified form of spring bar adapted for use in place

of the round spring bar illustrated in the other views.

The anchor as a whole comprises a jaw member 10 which comprises an upper jaw 11 and a lower jaw 12 of the customary configuration. The jaw member 10 is identical in Figs. 1, 2 and 3 of the drawings and fits the rail flange without distortion of the anchor jaw or the rail flange. The jaw member terminates in a depending foot 13 which, as shown in Fig. 3, is slightly offset to afford a bearing surface against the tie for the purpose of slightly canting or tipping the jaw member longitudinally of the rail in such a way as to exert a gripping or binding action on the upper and lower surfaces of the rail base as is shown in the anchors of all of my prior patents above referred to. The rail engaging jaw portions 11 and 12 of the anchor are extended in a fore and aft direction sufficiently to embrace the required length of the rail, but in order to reduce the amount of metal required, without sacrifice of the necessary strength, the rear surface of the anchor, behind the face thereof, is cut away at points above and below the gripping jaws, with the exception of upper and lower vertical reinforcing ribs 14 and 15, respectively. The jaws are oppositely positioned above and below the rail flange to firmly and frictionally engage the same and present plain bearing surfaces for contact with the upper and lower surfaces of the rail flange.

The lower jaw at a point inside of the rib 15 is thickened and extended to afford a short inwardly extending lug 16, which is bored or cored to receive an obliquely disposed spring bar which may be in the form of a round rod 17, or a flat bar 17^a, of sufficient length, when the anchor is applied to the rail, to extend beneath the base of the rail and may project beyond the farther edge thereof, as indicated in Fig. 1. This bar is given a driving fit within the socket bore, so that in effect the structure presents the character of a one piece anchor.

The normal obliquity of the spring bar is such as to bring its free end above the plane of the rail engaging face of the lower jaw, as shown in dotted lines in Fig. 1. The service position is shown in full lines also in Fig. 1. My wire spring performs no function whatever when the foot of the body of the anchor is in service pressure against

- the tie. It is only useful when, because of rail contraction, reverse creeping of rail, or other cause, the anchor has receded somewhat from the rail. The wire spring then functions to prevent transverse displacement of the anchor due to rail vibration. The spring gives the anchor, when the same is out of service contact with the tie, a slight transverse tilting or canting tendency. This supplements the normal frictional contact of the anchor with the rail flange, which is secured when the anchor is wedged upon the same in its application thereto. I have fully demonstrated by tests that this combined frictional hold upon the rail is sufficient to prevent transverse displacement of the anchor by rail vibration when the foot of the same is out of service pressure against the tie.
- 20 In order to further increase the gripping effect if desired, the gripping face of one of the jaws, preferably the lower jaw, may be provided with a shallow depression or pocket 19 into which a gritty or frictional substance, such as emery or the like, may be poured or housed, so that the gripping effect will be increased and the spring action supplemented in cases where an extreme degree of gripping effect is required, as, for instance, in tunnels or curves where an accumulation of grease on the rail renders an additional gripping action desirable.
- 25 By providing a spring bar of adequate length to afford engagement with a rail base of maximum width, the same anchor can be used with rails of lesser width, but configured to fit the jaws, so that within the range indicated the anchor possesses the characteristics of a universal anchor.
- 30 Although the invention has been described with particular reference to detail, it is not the intention, unless otherwise indicated in the claims, to limit the invention to the mechanism shown, since modification thereof may be employed without departing from the spirit of the invention.
- 35 I claim:
1. In a rail anchor, the combination of a jaw member providing upper and lower rail gripping jaws, one of the jaws being provided with a recess, an abrasive material housed within said recess, an inwardly extending spring bar socketed below the lower jaw and configured to normally extend above the plane of the engaged rail and adapted to be flexed downwardly by contact with the base of the rail when the anchor is positioned, substantially as described.
  2. In a rail anchor, the combination of a jaw member comprising upper and lower jaws adapted to embrace the edge of a rail, the lower jaw being provided on its acting face with a recess, a friction material housed within said recess and adapted to increase the frictional engagement of the jaw mem-

ber with the rail, substantially as described.

3. In a rail anchor, the combination of a rigid unyielding jaw member provided with an inwardly tapered jaw opening configured to snugly wedge upon and frictionally engage one flange of the rail, and a relatively flexible transversely extending bar socketed within the jaw member and extending obliquely upwardly to bring its free end above the plane of the base of the jaw opening and having a smooth upper contact surface formed to bring its free end into oblique bearing contact with the base of the rail when the bar is flexed downwardly by contact with the rail base and the tapered jaw member is frictionally wedged upon the rail flange, the bar being adapted to have engagement only with the under surface of the rail base, substantially as described. 75

4. In a rail anchor, the combination of a rigid unyielding jaw member provided with an inwardly tapered jaw opening configured to snugly wedge upon and frictionally engage one flange of a rail, and a relatively flexible transversely extending bar socketed within the jaw member and extending obliquely upwardly to bring its free end above the plane of the base of the jaw opening and having a smooth upper contact surface formed to bring its free end into oblique bearing contact with the base of the rail when the bar is flexed downwardly by contact with the rail base and the tapered jaw member is frictionally wedged upon the rail flange, the bar being adapted to have engagement only with the under surface of the rail base, substantially as described. 80

5. In a rail anchor, the combination of a

jaw member comprising upper and lower gripping jaws separated from one another to afford an inwardly tapering jaw opening configured to snugly wedge upon and frictionally engage one edge of a rail, a depending forwardly projecting foot carried by the jaw member and adapted to bear against a tie, the jaw member having a socket portion located at a point below the plane of the lower jaw, said socket portion being provided with an obliquely disposed socket bore, and a spring bar having its inner end socketed within said bore and obliquely extending therefrom sufficiently to bring its free end above the plane of the base of the engaged rail and adapted to be downwardly flexed by engagement with said rail when the anchor is positioned, substantially as described. 110

6. In a rail anchor, the combination of a jaw member comprising upper and lower gripping jaws separated from one another to afford an inwardly tapering jaw opening

configured to snugly wedge upon and frictionally engage one edge of a rail, a depending forwardly projecting foot carried by the jaw member and adapted to bear against a tie, a lug inwardly extending from the jaw member at a point below the plane of the lower jaw, said lug being provided with an obliquely disposed socket bore, and a

spring bar having its inner end socketed within said bore and obliquely extending ¹⁰ therefrom sufficiently to bring its free end above the plane of the base of the engaged rail and adapted to be downwardly flexed by engagement with said rail when the anchor is positioned, substantially as described.
